(57) **CLAIM**

The ornamental design for a powdered food shaker, as shown
and described.

DESCRIPTION

FIG. 1 is a front view thereof;

FIG. 2 is a rear view thereof;

FIG. 3 is a right side view thereof;

FIG. 4 is a top view thereof;

FIG. 5 is a bottom view thereof;

FIG. 6 is a referential perspective view thereof;

FIG. 7 is a cross-sectional view taken along 7—7 thereof;
and,

FIG. 8 is a referential view showing the situation in use.

The left side view is omitted, since it appears symmetrically
with the right side view.

The hand and powdered food shown in broken lines in FIG. 8
is for illustrative purposes only and form no part of the
claimed design.
